US0D1044856S

(12) **United States Design Patent** (10) Patent No.: **US D1,044,856 S**
(45) Date of Patent: ** Oct. 1, 2024

(54) **DISPLAY SCREEN OR PORTION THEREOF WITH A GRAPHICAL USER INTERFACE FOR AN APPLICATION LOGIN PAGE**

(71) Applicant: **SPLUNK Inc.**, San Francisco, CA (US)

(72) Inventors: **Tatsuya Hama**, North Vancouver (CA); **Ioan Popa**, Fremont, CA (US); **Melissa Hermanson**, Edgewood, WA (US); **Viet Quoc Nguyen**, Oakland, CA (US)

(73) Assignee: **SPLUNK Inc.**, San Francisco, CA (US)

(**) Term: **15 Years**

(21) Appl. No.: **29/858,419**

(22) Filed: **Oct. 31, 2022**

(51) LOC (14) Cl. **14-04**

(52) U.S. Cl.

USPC **D14/486**; D14/492

(57) **CLAIM**

The ornamental design for a display screen or portion thereof with a graphical user interface for an application login page, as shown and described.

DESCRIPTION

The FIGURE is a display screen or portion thereof with a graphical user interface for an application login page, showing our new design.

The surrounding rectangular box of broken lines shows a display screen or portion thereof and forms no part of the claimed design. The remaining broken lines show a graphical user interface for an application login page and form no part of the claimed design.

1 Claim, 1 Drawing Sheet
